LIQUID DISPENSING SYSTEM

Charles D. Fagan, Sharon, Pa., assignor to
Sharpsville Boiler Works Co., Sharpsville, Pa.,
a corporation of Pennsylvania

Application December 13, 1932, Serial No. 646,989

4 Claims. (Cl. 221—95)

This invention relates to liquid dispensing systems of the type ordinarily used for dispensing gasoline to motorists.

In systems of this sort, the liquid is usually pumped from an underground storage tank and delivered to the consumer through a flexible dispensing conduit. In one type of system, the dispensing conduit is provided with a valve adjacent its end; and the conduit is kept full of gasoline at all times, being dispensed only when the valve is open. In such systems, the operator usually starts the pump manually before taking the conduit or hose from the rack; and the pump runs continuously until it is again manually shut off. However, gasoline is delivered only when the dispensing valve at the end of the conduit is open. During the time intervals when the dispensing valve is closed, the pump circulates the liquid through a by-pass which is provided to prevent the building up of excessive pressure. The operation of the pump at times when liquid is not being dispensed is wasteful of power and has other disadvantages.

The pump is located above ground and it sucks the liquid up from the subterranean storage tank through a conduit that extends downwardly to the bottom of the tank. At the bottom of this suction conduit there is ordinarily provided a check-valve or "foot-valve" which is intended to keep the conduit full of liquid. These foot-valves are not readily accessible for inspection or repair, and hence it not infrequently happens that the foot-valve will become leaky. With a leaky foot-valve, the suction conduit drains while the pump is standing idle, with the result that on the next starting of the pump, the air has to be pumped out of the suction conduit and this air may be metered as gasoline delivered to the motorist. In other instances, the pumping of air which results in short measure to the motorist is occasioned by air leaking into the suction conduit at some point between the supply tank and the pump. Thus, even if the operator discovers that air is being pumped, he will not know whether it is due to a leaky suction line or a leaky foot-valve, and will not know where to look for the trouble.

An object of the present invention is to provide for effective elimination of air drawn to the pump, without metering it and thus giving the consumer short measure.

Another object of the invention is to provide a liquid dispensing system which automatically eliminates air and apprises the operator that air is being pumped, and preferably also indicates

the source of the defect which leads to the presence of air.

Another object of the invention is to simplify and improve the operation and/or construction of liquid dispensing systems.

Fig. I is a perspective view showing the essential parts and arrangement of an illustrative system embodying the present invention.

Fig. II is a plan view, partially in section, showing an illustrative air separator unit.

Fig. III is a vertical longitudinal section through the air separator unit, taken approximately on line III—III of Fig. II.

Fig. IV is a vertical cross section of the air separator unit, taken approximately on line IV—IV of Fig. II.

Fig. V is an elevation, partially in section, looking from the liquid discharge end of the air separator unit.

Fig. VI is a detail of the air separator unit taken approximately on line VI—VI of Fig. III.

Fig. VII is a horizontal sectional detail view, taken approximately on the line VII—VII of Fig. VI.

Fig. VIII is a vertical section showing a valve which is interposed between the air separator unit and the meter.

Reference will now be had to Fig. I of the drawings. A frame comprises four angle iron standards 1 (three shown), to which are secured a base member (not shown), a cast head member 2, and various intermediate iron cross pieces 3. Bolted or screwed to the cross pieces 3 and/or the standards 1 is an air separator unit designated as a whole by 4. The lower part of the separator unit 4 is provided with a depending portion 6 on one side of which there is bolted to the separator unit an electric motor 7, and on the other side of which there is bolted to the separator unit a liquid pump 8. The liquid pump 8 may be of any suitable type such as a gear pump or the pump shown in the application of Fagan & Swank, Serial No. 559,382, filed August 26, 1931. The pump 8 is connected to be driven by the motor 7 through any suitable means such as a belt or chain 9. Also secured to the air separator 4 is an automatic safety switch unit 10, which controls the motor 7.

Gasoline is drawn from a supply tank through suction conduit 11 to pump 8, which forces it through the air separator unit 4 and thence through valve 12 (described later), strainer 13, meter 14, flow indicator 16, and dispensing conduit 17. A pressure switch pipe 17—a connects the outlet conduit 17—b with the pressure op-

erated switch 10. As usual, the meter 14 is provided with one or more dials 14^a which indicate the volume of gasoline passing through the meter. The particular construction of the meter 14 forms no part of the present invention; it may be of any suitable and known type. The flow indicator 16 may also be of any suitable and known type. Specifically, it may be of the type shown in the application of Fagan & Swank, Serial No. 541,628, filed June 2, 1931, or of the type shown in the application of Fagan, Serial No. 636,120, filed October 4, 1932.

At the end of the conduit 17, there is a normally closed dispensing valve 18 of known type adapted to be opened by grasping the lever 19. The lever 19 is within a guard 20; and both the guard and the lever are slotted so that the end of the hose may be hung, as shown, upon a pivoted hook 21, with the flexible end 22 of the hose projecting, as shown, to the interior of the structure, where it is protected from rain. The switch unit 10 is of known type, and may be of the construction shown in the application of Fagan et al., Serial No. 462,478, filed June 20, 1930. When released for action, this unit operates to automatically start and stop the motor 7 in response to opening and closing of the dispensing valve 18; and thus the motor 7 and pump 8 run only when gasoline is being dispensed. To prevent accidental starting of the motor, the switch unit 10 is normally disabled through safety connection 23 from pivot hook 21. When the nozzle is hung in the position shown in Fig. I, the movement of rod 23 actuates a series switch (preferably double pole) which opens the line; or in the alternative, rod 23 may disable switch 10 as shown in the application of Fagan et al., Serial No. 462,478, filed June 20, 1930. The operator having removed the nozzle from the hook 21, manually raises hook 21, thus removing the safety and permitting the switch 10 to start the motor when dispensing valve 18 is opened. When the dispensing valve is closed, switch 10 automatically stops the motor 7; and the safety is restored when the nozzle is hung in place upon the hook 21.

Reference will now be had to Figs. II to VII of the drawings. The air separator unit 4 comprises a casing, designated as a whole by 30, within which there are partitions or baffles 31 and 32 sub-dividing space within the casing into a series of communicating compartments 33, 34, and 35. The structure may be cast; and various threaded recesses 36 are provided for the purpose of permitting the motor 7 and the pump 8 to be bolted into place and also for the purpose of permitting the entire unit to be bolted or screwed to the supporting frame shown in Fig. I. To facilitate the molding operation, there are various apertures which, when the casting is completed, are closed with suitable plugs 37. These plugs also serve for draining and giving access to various portions of the interior. At the tops of the chambers 33, 34, and 35, there are removable apertures plugs 33^a, 34^a, and 35^a to permit the escape of air. To permit access to the air escape plugs and removal and replacement of the same, there is provided on the top shell of the casing corresponding removable plugs, two of which are shown at 33^b and 35^b. The air escape plugs lead to horizontal passageways 33^c, 34^c, and 35^c, all of which lead to a collection chamber 38.

Depending beneath chamber 33 is a hollow element 6 divided by a horizontal partition 40 into two sections 41 and 42. Suitable screens 41—a

and 42—a are provided in the path of liquid flow. Section 41 communicates through port 45 with chamber 46, which in turn is adapted to be placed in communication with the liquid supply tank through connection 44, and is also adapted to be placed in communication with collection chamber 38 through conduit 47. Section 42 is in direct communication with chamber 33, as shown in Fig. III. The pump 8 is mounted in the position shown in full line in Fig. I, and in dot-dash lines in Fig. III; and when the pump is in operation, it acts to draw liquid from the supply tank through connection 44, port 45, to chamber 41 and into the pump, from which the liquid is forced into space 42 and thence through chambers 33, 34, and 35 successively. Above chamber 35 there is a recessed portion 48 through the bottom of which there is threaded connection 49 of the line leading to the meter 14, as shown in Fig. I.

Within collection chamber 38 there is a float 50 mounted for vertical movement and connected through lever mechanism 51 to open valve 52 when the float rises. The valve 52 is attached to the short arm of the lever and the float 50 is attached to the long arm of the lever. When valve 52 is open, liquid within the collection chamber 38 drains through passageway 47 to chamber 46, from whence it passes through port 45 to the suction side of the pump 8.

As gasoline is forced through the chambers 33, 34, and 35 successively, air in the gasoline separates therefrom in such chambers and leaves the chambers through the air outlet plugs 33^a, 34^a, and 35^a. Through passageway 33^c, 34^c, and 35^c, the escaping air is conducted to the top of collection chamber 38, from whence the air passes out through pipe 56 to whistle 57 (Fig. I). Any gasoline which may escape through the plugs 33^a, etc. falls into collection chamber 38; and when sufficient gasoline has collected in chamber 38, float 50 rises and permits the gasoline to discharge from the bottom of chamber 38 through passageway 47 to the intake side of the pump 8.

I have found that the separation of the air from the gasoline in chambers 33, 34, and 35 is improved if a slight pressure is maintained within such chambers during the operation of the device. For this purpose, there is provided valve 12, shown in detail in Fig. VIII, which imposes a retarding influence upon the gasoline as it leaves the separator 4. The valve 12 comprises a weighted valve element 60 which seats by gravity against a seat 61, so that the gasoline in passing from the separator 4 to the meter 14 must raise the valve 60 against the force of gravity. Thus the valve is automatically opened by the flow of gasoline, but acts to place a predetermined retarding effect on the flow and thus maintain a pressure within the chambers 33, 34, and 35 while the gasoline is flowing. When the pump is standing idle, an increase of temperature may expand the gasoline within the hose 17; and to prevent this from building up an undesirably high pressure in the hose, relief is provided through a reverse acting valve associated with valve element 60. In the center of element 60 there is a port 64 normally closed by spring pressed valve element 65. However, when the pump is standing idle with valve 60 closed, the building up of a pressure 70 in hose 17 will cause valve element 65 to open and relieve the pressure by allowing gasoline to flow from the hose to separator 4, which is open to the atmosphere through whistle 57.

It will be noted that the air is eliminated from 75

the gasoline before it is metered, and hence air present in the gasoline does not cause short measure to be delivered to the consumer. If the foot valve in the supply tank leaks, suction conduit 11 (Fig. 1) will drain while the pump is standing idle; and when the pump is started, this conduit full of air will have to be pumped out and eliminated before gasoline is delivered. Whistle 57, of course, apprises the operator whenever air is being eliminated; and in the case of a leaky foot valve, the whistle will blow for a short time whenever the pump is first started after having been idle for quite an interval. Thereafter during the continuous operation of the pump, there will be no air to eliminate and hence the whistle will be silent. Thus, by the fact that the whistle blows for a time and then stops while the operation of the pump is continued, the operator will be advised of the fact that the air being eliminated was due to an initially empty conduit 11 or, in other words, to a leaky foot-valve. However, suppose that there is an air leak into line 11 so that air is continuously drawn into the line during the pumping of gasoline. In this case, air will be eliminated as long as the pumping is continued, and thus the whistle 57 will operate continuously during the pumping operation. This will apprise the operator that the difficulty is due to an air leak into line 11.

It will be apparent that in the absence of a proper set-up, there would be danger of gasoline being pumped out through the whistle 57, which would present a serious fire hazard. With the usual pump system, the pump is manually started and stopped, but delivers gasoline only while the dispensing valve at the end of the dispensing conduit is open. When the dispensing valve is closed, the pump (in the usual system) circulates the gasoline idly through a by-pass. It is apparent that with such idle circulation of gasoline, there would be danger of the gasoline working to whistle 57; but with applicant's system the motor is automatically started and stopped in response to opening and closing the dispensing valve 18 and hence the danger of gasoline reaching whistle 57 through circulation of the gasoline while it is not being dispensed is eliminated. Furthermore, applicant provides collection chamber 38 to col-

lect any gasoline which may pass through the air discharge ports 33^a, etc. This collection chamber 38 is connected to be automatically emptied through the suction from pump 8 whenever the pump is in operation; and the port closed by valve 52, passageway 41, etc. are each of greater area than the sum of the discharge areas of plugs 33^a, etc. Hence, it is impossible for collection chamber 38 to fill with gasoline and permit the gasoline to be forced out through the 10 whistle 57.

The present invention may, of course, be embodied in forms other than the one particularly disclosed and hence the foregoing disclosure is merely illustrative in compliance with the patent 15 statutes and is not to be considered as limiting the scope of the claims.

What is claimed is:

1. A liquid dispensing system comprising: a supply tank; an air separator; a dispensing conduit; means to induce liquid flow from the supply tank, through the air separator, to the dispensing conduit; and means to indicate the separation of air from the liquid in the air separator.

2. A liquid dispensing system comprising: a supply tank; an air separator; a dispensing conduit; means to induce liquid flow from the supply tank, through the air separator, to the dispensing conduit; and an audible signal automatically operable when air is being separated from the 30 liquid in the air separator.

3. A liquid dispensing system comprising: a supply tank; an air separator having an air discharge port; a dispensing conduit; means to pump liquid from the supply tank, through the 35 air separator, to the dispensing conduit; and a signal operable by air escaping through said discharge port.

4. A liquid dispensing system comprising: a supply tank; an air separator having an air discharge port; a dispensing conduit; means to pump liquid from the supply tank, through the air separator, to the dispensing conduit, an air discharge conduit connected to said port, said conduit extending upwardly to a level substantially higher 45 than said air separator; and a whistle on the end of said air discharge conduit.

CHARLES D. FAGAN.
